UNITED STATES PATENT OFFICE.

WILLIAM R. POLSON AND WILLIAM GRANT, OF BRUNEAU, IDAHO.

SPARK PLUG.

Application filed June 20, 1924. Serial No. 721,287.

To all whom it may concern:

Be it known that we, WILLIAM R. POLSON and WILLIAM GRANT, citizens of the United States, residing at Bruneau, in the county of Owyhee and State of Idaho, have invented certain new and useful Improvements in Spark Plugs, of which the following is a specification.

This invention relates to sparking devices for use in connection with internal combustion engines and relates particularly to spark plugs.

The primary object of this device is the provision, in a manner as hereinafter set forth, of a spark plug so constructed that a plurality of sparking points are provided in order that a spark will always be had in the cylinder should the regular points of the primary and ground electrodes become carbonized and useless.

The invention contemplates the provision of a plug having a shell of ordinary construction and having a porcelain body within the shell having a constricted substantially elongated lower portion and having the main electrode, running through the porcelain, broken and the ends thereof turned outwardly to protrude from the side of the elongated lower portion providing the first sparking points. The lower end of the electrode extends from the terminal portion of the porcelain, in the usual manner, to form a spark gap with a ground electrode extending inwardly from the shell of the plug.

The final object of this invention is the provision, in a manner as hereinafter set forth, of a spark plug of simple construction, of few parts, strong, and inexpensive to manufacture.

The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claim.

In the drawing:

Figure 1 is a side elevation of a spark plug constructed in accordance with this invention.

Figure 2 is a modification showing the

provision of a plurality of sparking points.

Referring to the drawing in detail, numeral 1 indicates the body of the shell of the plug, the lower portion 2 thereof being peripherally threaded as at 3, as is the usual construction, for insertion into the aperture in an engine cylinder. The shell 1 has the usual longitudinally extending bore 4 therethrough, the upper portion 5 being of greater diameter than the lower portion and interiorly threaded at its upper end as at 6 to take the threaded lower portion 7 of the gland or packing nut 8.

The body of the insulating portion used in conjunction with this device is indicated at 9, which body has formed thereabout at the lower portion thereof the enlarged girdle 10 which is adapted to position in the enlarged portion 5 of the passage 4 and is held therefrom by the annular washer 11 at the lower portion and has the washer 12 upon the upper shoulder against which the lower edge of the collar 7 bears. This collar 7 as shown fits snugly about the body portion 9. The upper portion of the body is extended a substantial distance above the plug as indicated at 13 and the lower portion of the body has depending therefrom the substantially elongated cylindrical portion 14 which is of materially less diameter than the body portion as shown and is freely suspended in the recess or central bore 4 of the shell.

Extending through the center of the body of insulation and the upper and lower portions 13 and 14 thereof, is a two part primary electrode 15 and 15' which, as shown, at its lower portion, extends substantially half-way the length of the portion 14 of the insulation and is there bent at right angles as at 16 and projected through the side of the lower portion 14 as shown and there has the terminal ends bent downwardly as at 17 parallel with the side of the terminal portion 14. The terminal end of the lower portion 14 has embedded therein the angled lower portion 15' which comprises a vertical portion 18 which projects from the free end of the portion 14 as shown and is in alignment with the main portion of the electrode 15, and the upper end is formed at right angles as at 19 to extend through the side of the portion 14 in alignment with the angled extension 16 of the main electrode and the outer or free end of this angled portion 19 is bent upwardly at right angles as at 20 in such a manner that the end thereof is

adjacent but spaced from and in alignment with the downturned portion 17. A ground electrode 21 in the form of a right angled member, is provided, having one leg embedded in the wall of the shell as shown and having the other leg extended outwardly and spaced from the side of the depending terminal end 18 of the lower portion 15.

In Figure 2 of the drawing, there is shown 10 a modification of the structure shown in Figure 1, provision being made here for the formation of a plurality of spark gaps before the final spark or sparking point is reached. The lower portion 14 of the porcelain has 15 embedded therein the horizontally positioned shank 22 of a plurality of T-shaped members 23. The heads of these T-shaped members, indicated at 24, are in alignment as shown and are slightly spaced one from the other and further are positioned between the points 17 and 20 as shown. The construction in this form is the same as in Figure 1 as can be clearly seen, with the exception that the points 17 and 20 are spaced 25 a sufficient distance apart to allow for the insertion therebetween of the aligned heads 24 of the T-shaped members 23. It will thus be seen that three spark gaps 25 are provided before the final spark gap is reached, 30 thus giving a series of sparks in the cylinder and, if one of the points becomes fouled the other points will continue to fire.

It is of course understood that the device is not limited to the use of two of these T-shaped members to provide three extra 35 sparking gaps, but as many of the members may be used as is desired.

When in use, if the spaced ends of the portions 18 and 21 become carbonized to such

an extent that a spark is no longer formed 40 therebetween, the points 17, 20, 25 positioned at the side of the portion 14 will continue to spark, thus carrying on the action of the cylinder, and in view of the fact that these points are shielded within the shell 45 bore 4, it is less likely that they will get out of commission.

From the foregoing description, it may 50 be seen that an improved spark plug is provided, which has the advantage of more than one sparking point thus preventing failure of the cylinder due to the carbonization of the lower of the points.

Having thus described our invention what 55 we claim is:

A spark plug comprising, a shell, a body 60 of insulation therein having the lower portion formed to provide an elongated cylindrical body of relatively small diameter and wholly within said shell, an electrode within said body formed into an upper and a lower portion, the lower end of the upper portion being bent at right angles to extend through and beyond the side of said elongated body and the upper end of the lower portion being bent at right angles to extend through and beyond the side of the body parallel with the first mentioned bent portion, the outer ends of said bent portion being in 65 spaced relation to provide sparking points, and a ground electrode spaced from the lower end of said lower portion to provide a second sparking point.

In testimony whereof, we affix our signatures hereto.

WILLIAM R. POLSON.
WILLIAM GRANT.
